Inventor,

Edwin Snape,
by his attorney,
J. S. Brown.

UNITED STATES PATENT OFFICE.

EDWIN SNAPE, OF BROOKLYN, NEW YORK.

IMPROVEMENT IN DINNER-PAILS.

Specification forming part of Letters Patent No. 147,290, dated February 10, 1874; application filed December 1, 1873.

To all whom it may concern:

Be it known that I, EDWIN SNAPE, of the city of Brooklyn, in the county of Kings and State of New York, have invented new and useful Improvements in Dinner-Pails; and I do hereby declare that the following is a full and exact description thereof, reference being had to the accompanying drawings and to the letters of reference marked thereon making a part of this specification.

My invention has for its object to provide a dinner-pail for workmen in which their dinner can be carried from their home in the morning and, in a few minutes before eating, it can be made warm without removing it from the pail, or without regard to location or condition. The nature of my invention consists in a dinner-pail provided with a heating-lamp underneath it, admitting the draft to support combustion from below, and with two rims surrounding the lamp and the bottom of the pail, and lapping by each other, with a space between them and the lamp and between each other, opening also over the inner and under the outer rim, for the passage of the products of combustion from the lamp, while protecting the flame thereof against the wind outside, all substantially as herein specified.

To enable others skilled in the art to make and use my invention, I will proceed to describe its construction and operation.

Figure 1 is a view of the bottom of the apparatus; Fig. 2, a central vertical section thereof; Fig. 3, a side view of a part detached.

Letters of like name and kind indicate like parts in each of the figures.

A represents the body of the dinner-pail, made in the ordinary way, in the bottom of which it is designed to carry tea or coffee, while the upper portion B is intended for food. The portion B is made separate from A, and fits loosely but closely into A, and can be readily

removed therefrom. C represents a cup which serves the purpose of a cap when turned bottom up over the portion B, it being so constructed that it is not likely to fall off while carrying. D represents a lamp which of itself is of the ordinary kind for either oil or spirit. Around the wick-tube a of the lamp D is a perforated cylinder, I, through which the air is made to pass when the said cylinder extends upward nearly to the bottom of the portion of the pail A at the point O. The lamp D is secured by any well-known means to a base, G, the bottom of which is fully perforated for the purpose of allowing a supply of air to the burner. At the lower part of the portion of the pail A is a projecting rim, H, which extends outward from and below the bottom of the portion A, and on the inside of this rim H is another rim, J, secured to the rim H, so as to form an annular space between the two rims. The inner rim J, it will be observed, is set a little away from the bottom of the portion A, so as to form a space between them, as seen at e, for the passage of the products of combustion from the lamp D, as shown, in the direction of the arrows, and, at the same time, to prevent the wind from blowing out the lamp. L L L represent the legs on which the pail stands. P represents the bail or handle by which the pail is carried.

Having thus described my invention, what I claim as new, and desire to secure by Letters Patent of the United States, is—

The combination of the dinner-pail A, provided with the rims H J, arranged as described, and the lamp D, substantially as and for the purpose herein specified.

EDWIN SNAPE.
